UNITED STATES PATENT OFFICE.

ROBERT LAMBERT MURRAY, OF BUSHEY HEATH, ENGLAND, ASSIGNOR TO TELEPHONE
MANUFACTURING COMPANY LIMITED, OF LONDON, ENGLAND.

TELEPHONE TRANSMITTER.

Application filed August 24, 1921. Serial No. 494,770.

To all whom it may concern:

Be it known that I, ROBERT LAMBERT MURRAY, a subject of the King of England, residing in Bushey Heath, Hertfordshire, 5 England, have invented certain new and useful Improvements in Telephone Transmitters, of which the following is a specification.

This invention relates to telephone transmitters of that type of which the diaphragm or a "pad" thereon is intended to be held in contact with a surface of portion of the user's person, hereinafter referred to in a general sense as the throat in contradistinction to the type intended to be held near the mouth to receive sound transmitted through the air. The term "pad" is intended to denote any projection carried upon the diaphragm itself so as to be interposed between the diaphragm and the surface against which it is to be pressed so that vibrations are transmitted mechanically through the said projection.

The object of the present invention is 25 partly to prevent undue pressure being exerted between the diaphragm or "pad" and the user's throat and partly to provide a construction by which the transmitter shall be less liable to displacement from a convenient 30 position than has heretofore been the case.

The present invention therefore provides a telephone transmitter of the type described provided with one or more members carried by the diaphragm-support and extending therefrom to bear upon the surface of the user's person around or closely adjacent to the surface upon which the diaphragm or a "pad" thereon presses.

Conveniently, according to this invention, 40 a telephone transmitter of the type described is provided with a rigid or other shield carried by the diaphragm support, apertured to permit the diaphragm or a "pad" thereon to project through the aperture and shaped 45 or dimensioned to bear upon the user's throat surrounding or closely adjacent to that part thereof against which the "pad" is pressed.

Preferably, according to this invention, a 50 telephone transmitter of the type described is provided with a shield of elongated form (for example of elliptical form) centrally apertured to clear the diaphragm and so carried by the diaphragm-support as to permit the diaphragm to project beyond the

shield and that the longer dimension of the shield extends in the direction of the length of the user's neck when in use.

The accompanying drawings illustrate, by way of example only, two embodiments of the present invention which give good results,

Figure 1 being a perspective view of one form of telephone having a throat-transmitter embodying the present invention,

Figure 2 a sectional view taken vertically through the centre of Figure 1, and

Figure 3 a side view of a telephone handset embodying the invention, having part of the transmitter broken away to reveal its construction.

Referring first to Figure 2, the transmitter 1 is built together with a receiver 2, upon a foundation ring 3 common to them both. The receiver magnet 4 is encircled by the ring and is mounted upon a base-plate 5 75 which serves to close one otherwise open side of the ring, and the other open side is closed by the receiver diaphragm 6 which is covered by a dished flanged cap 7, whereof the flange 8 surrounds the ring and is secured to the latter by screws 9. The concavity of the cap is towards the diaphragm 6 and a duct 10 leads from the chamber 11 thus formed between the diaphragm and the cap through the tubes 12 to the ear pieces (not shown).

On the exposed side of the base-plate, that is to say the side opposite to that which carries the receiver magnet, the transmitter is mounted. The transmitter is provided with a diaphragm 13 to which is secured a cup 14 in which carbon pellets are received and retained and with a contact plate 15 for the carbon pellets, which plate is secured to the base-plate 5 by a screw. The diaphragm is held in position by a flanged securing ring 16 whereof the flange 17 engages the diaphragm 13 and the body is secured to the foundation ring 3 in any convenient manner. The said securing ring 16 carries an elliptical larynx shield 18 of ebonite having a circular central aperture 19 to allow the transmitter diaphragm to protrude slightly therethrough. The said aperture is of slightly larger diameter than the flange 17 upon the securing ring so as to ensure complete freedom of the diaphragm from direct mechanical contact with the shield. A resilient metallic washer 20 is interposed between the diaphragm and base-

100

105

110

plate and these four said parts are all held in position by the said securing ring. The securing ring is provided with two diametrically opposite gaps 21 which receive 5 and engage lateral projections 22 upon the base-plate, which projections are intended to receive the attaching straps, indicated in chain lines at 23 whereby the whole device is held in position upon the user's 10 throat. The longer axis of the shield lies transversely across the line of the attaching straps, that is in the plane of the face of the section shown in Figure 2.

When in use the larynx shield serves to 15 prevent the pressure of the attaching straps from being entirely transmitted through the diaphragm to the larynx and diverts part of this pressure to the surrounding muscles thereby relieving the pressure on the larynx 20 and in some measure predetermining its magnitude.

The shield, moreover, enables the diaphragm to be kept properly presented to the throat with less pressure than was heretofore required since without the shield the weight of the device constantly tended to 25 make it tilt outwardly about its lower edge with the result that the lower portion of the diaphragm alone remained in contact 30 with the throat, unless an inconveniently large pressure was maintained by the attaching straps; the downwardly projecting portion of the shield affords a better leverage 35 for the attaching straps enabling the diaphragm to be held against the throat with less tension in the straps. It is also found that by this means the transmitter is less liable to displacement from its correct location upon the throat, which location appears 40 to be a slight depression, or at least a part occupied with relatively softer tissues, lying between two muscles, tendons or other relatively harder structure of the neck of the user. The shield may also serve to aid in 45 transmitting from the throat to the microphone.

In Figure 3 is shown a handset of the usual type in which a rigid tube 24 supports a receiver 25 secured by a screw 26 at one 50 end and a transmitter 27 at the other end and has a hand-grip 28 provided about its middle. The transmitter, however, is of the kind hereinbefore described as for application to the outside of a user's throat. 55 It comprises a diaphragm 29 carrying the pellet-cup 30, and a dished plate 31 carrying the pellet contact 32, the plate and the diaphragm being held together at their edges in any suitable manner.

60 These transmitter parts are held in position against the forward extremity of a cup-shaped casing 33 by a larynx shield 34 of vulcanite or similar substance of which an inwardly directed flange 35 engages a co- 65 operating outwardly directed edge 36 of

the diaphragm. The shield is screwed on to the outside of the casing 33, for which purpose it may be provided with a screw-threaded metal lining. The shield is also circular in shape and as in the construction 70 previously described is formed with a central aperture through which the diaphragm 29 slightly protrudes, the aperture being of such diameter that it is clear of the protruding portion of the diaphragm. 75

If desired, the receiver of this hand set may be permitted a certain amount of pivotal movement about its securing screw 26 so that it can be properly seated against the user's ear notwithstanding the angle at 80 which the supporting tube may have to be held in order to bring the diaphragm into full contact with the user's throat.

This construction, obviously is particularly suitable for use in circumstances in 85 which a throat-transmitter is desirable, but in which it is not desired to have the instrument secured about one particular user's head.

It will be appreciated that the aforesaid shields are not the only forms of shield which will fall within the scope of this invention. For example, oppositely projecting lateral arms of resilient material may be 90 employed and these may be two in number, 95 one on either side, or more, and their free ends may be provided with pads or not, as desired.

What I claim as my invention and desire 100 to secure by Letters Patent is:—

1. In a telephone transmitter, the combination of a support, a microphone carried thereby, vibration-transmitting means operatively connected with the microphone for directly receiving sound-vibrations from a part of the human body and for transmitting the same to the microphone, and pressure-distributing means carried by the support and spaced radially away from the margin of said vibration-transmitting means, which latter means extends axially in front of the pressure-distributing means whereof the front face is situated so far rearwardly of the front face of said vibration-transmitting means as to constitute a pressure-distributing support for the transmitter when the front face of the vibration-transmitting means bears against a part of the human body, substantially as described. 115

2. In a telephone transmitter, the combination of a support, a diaphragm arranged to receive directly sound-vibrations from a part of the human body, a microphone operatively connected with said diaphragm and mounted between the same and said support, and a shield that constitutes the sole means for holding said diaphragm and said microphone in position on the support, which shield is carried by the support and has an aperture through which said dia- 125 130

- phragm extends axially, with marginal clearance, beyond the front face of the shield, which front face is situated so far rearwardly of the front face of said diaphragm as to constitute a pressure-distributing support for the transmitter when the front face of the diaphragm bears against a part of the human body, substantially as described.
- 10 3. In a telephone transmitter, the combination of a support, a diaphragm arranged to receive directly sound-vibrations from a part of the human body and having an outwardly-directed flange, a microphone oper-
15 atively connected with said diaphragm and mounted between the same and said support, and a centrally apertured shield of ellipti-
- cal form carried by said support and engaging said flange and thereby holding said diaphragm and said microphone in position 20 on said support, which shield has its front face situated so far rearwardly of the front face of said diaphragm as to constitute a pressure-distributing support when the front face of the diaphragm bears against a 25 part of the human body, substantially as described.
- In testimony whereof I have signed my name to this specification in the presence of two subscribing witnesses.
- ROBERT LAMBERT MURRAY.
